(57) **CLAIM**

The ornamental design for a 'micro-print detector,' as shown.

DESCRIPTION

FIG. 1 is a perspective view of a 'micro-print detector' showing my new design;

FIG. 2 is a right side elevation view thereof;

FIG. 3 is a top plan view thereof;

FIG. 4 is a left side elevation view thereof;

FIG. 5 is a bottom plan view thereof;

FIG. 6 is a front elevation view thereof; and,

FIG. 7 is a rear elevation view thereof.
